UNITED STATES PATENT OFFICE.

JOHN SMITH, OF NEW YORK, N. Y.

DEVICE FOR REPLACING AND ADJUSTING COILS IN FIELD-GUNS.

1,136,728.

Specification of Letters Patent. Patented Apr. 20, 1915.

Application filed December 24, 1914. Serial No. 878,955.

To all whom it may concern:

Be it known that I, JOHN SMITH, a citizen of the United States, and a resident of the city of New York, borough of Brooklyn, in the county of Kings and State of New York, have invented a new and Improved Device for Replacing and Adjusting Coils in Field-Guns, of which the following is a full, clear, and exact description.

10 My invention relates to means for changing the resilient member in the recoil mechanism of a field gun, also whereby the recoil mechanism may be tested.

The object of the invention is to provide 15 a simple and inexpensive device which can be easily and quickly applied to a field gun, which will obviate the present use of block-and-fall with the abutting members necessary therefor, and by which device the recoil setting or adjusting of the recoil can be 20 easily and quickly done without in any way using any of the other field pieces of the battery for abutment or other purposes.

With the above and other objects in view, 25 the nature of which will more fully appear as the description proceeds, the invention consists in the novel construction, combination and arrangement of parts as herein fully described, illustrated and claimed.

30 In the accompanying drawings, forming part of the application, similar characters of reference indicate corresponding parts in all the views, and—

Figure 1 is a rear elevation of the device; 35 Fig. 2 is a plan view thereof; Fig. 3 is a detachable member of the device; Fig. 4 shows the application of my device to a field gun during the placing of a new coil or during the resetting of the recoil mechanism; and Fig. 5 shows the device applied 40 when testing the recoil mechanism.

Referring to the drawing, 6 represents the field gun having a recoil controlling mechanism 7. To reset the recoil mechanism or 45 to place a new spring or to refill the recoil mechanism with oil, it is necessary either to compress the spring or to move the gun to extreme recoil; and for this I provide a device consisting of a rectangular frame 8 having detachable pegs or standards 9 which support the frame. Said pegs 9 are 50 preferably made to fit sockets forming part of the frame, and thus make the frame more stable.

55 Mounted to rotate in the frame is a drum 10 which is geared to a stub-shaft 11 with

which a detachable crank 12 is associated and whereby the drum may be rotated. A pawl 13 is attached to the frame and made to engage the pinion or gear mounted on the stub-shaft 11. The engagement between the pawl and gear is maintained by gravity acting on the pawl. A brake mechanism can be attached to the drum 10 or to the stub-shaft 11, as desired.

To strengthen the frame 8 and form an additional bearing for the stub-shaft 11, a bar 14 is provided extending between the front and rear of the frame and parallel to the sides in which the drum and stub-shaft 60 bear. The corners of the sides adjacent the front are provided with hooks 15, similar hooks 15 being attached to the rear of the frame adjacent the corners. The frame 8 is also provided with a transverse member 16 65 extending between the sockets at the front of the frame. Said member is preferably made removable by providing eyelets 17 at the ends thereof through which the front pegs may be freely passed. This member 16 70 is adapted to rest on a trail 27 transversely thereof when my device is assembled and applied to the field gun 6. At the rear of the frame 8, substantially in the center thereof, a bar 18 is pivotally mounted. The 75 length of said bar is such that when the members 16 rest on the trail, the rod 18 will also engage the trail when placed in a substantially vertical position (see Figs. 4 and 5).

To prevent the movement of the device, that is of the frame 8, when a pull is applied to the drum 10 a chain or other flexible member 19 is attached to one of the hooks 15 at the front. Said shaft or flexible member is made to pass through a lunette 26 of the trail, then through the rear hook 15 which is adjacent the side to which the chain is attached, then through the other hook 15 in the rear, then again through the 80 lunette 26, then attached to the other hook 15 at the front. This chain or flexible member will, therefore, bind the device to the trail of the gun. The rod 18 and the member 16 prevent the downward movement of 85 the device, while the flexible member 19 prevents the upward movement of the rear of the device. To prevent the pegs 9 from sinking into the ground boards are placed under the pegs when my device is mounted 90 on a field gun. The flexible member 20 provided on the drum 10 preferably has one

end thereof secured to the drum, while the other end carries a suitable hook or attachment whereby it can be attached to a screw 28 threaded into the end of a cylinder 21 for which a threaded opening is provided. The other end of the cylinder is provided with a flange engaging one end of a coil spring 22, the other end of the coil spring abuts against the rear end of the cradle 23. 10 By winding the flexible member 20 on the drum 10, the cylinder 21 is pulled into the cradle while compressing the coil spring 22. When the proper compression is obtained the cradle head 24 can be placed in position. 15 At this time the cylinder end which is connected with the flexible member 20 will pass through the cradle head and engage a bracket 25 of the gun to which it can then be secured. The flexible member 20 can then 20 be detached from the cylinder; and if the cylinder is filled with oil, the gun is ready for operation and my device can then be removed by simply detaching the chain 19 from the lunette 26 of the trail 27. The removable parts can then be detached from 25 the frame and the same stored in the supply carriage.

When it is desired to test or time the recoil, the flexible member 20 is made to engage the muzzle of the gun 6 (see Fig. 5); and by pulling the gun to the extreme recoil position, as shown in Fig. 5, and then disengaging the pawl 13 from the pinion, the time the gun-piece takes to return to its 35 normal position can be measured. The cylinder can be refilled with oil, also, by the aid of my device, as can be easily seen.

It will be noted that by means of my device the recoil mechanism can be easily and 40 quickly reset, that the coil 22 can be quickly exchanged or the cylinder filled with oil, and also the time of recoil measured. It does not require any special abutments or blocking of the wheels of the gun-piece; it 45 eliminates the use of the other field pieces for resetting, as is commonly done, and, consequently, is a great saver of time, and permits the use of the other field guns while this one to which the device is applied is 50 reset.

From the foregoing description, taken in connection with the accompanying drawings, the advantage of the construction and operation of the device shown will be readily 55 understood by those skilled in the art to which the invention pertains; and while I have described the principle of operation, together with the device which I now consider to be the best embodiment thereof, I 60 desire to have it understood that the device shown is merely illustrative and that such

changes may be made as are within the scope of the appended claims.

Having thus described my invention, I claim as new and desire to secure by Letters Patent:

1. In combination with a field gun having a recoil mechanism and a trail, a device for resetting said recoil mechanism comprising a frame, means for supporting said frame 70 over the trail, abutting members from the frame to the trail, a flexible member connecting the front and rear of the frame to the end of the trail, and a winch mechanism on said frame.

2. In combination with a field gun having a trail, a device of the class described comprising a frame, removable supports for the frame whereby the same is supported above the trail, abutting members from the frame 80 to the trail, hooks at the sides adjacent the front and at the rear adjacent the sides of the frame, a flexible member connecting said hooks to the end of the trail, and a winch mechanism on said frame.

3. In combination with a field gun having a trail, a device of the class described comprising a frame, detachable supports for the frame whereby the same can be mounted above the trail, abutting members from the 90 frame to the trail, hooks at the front and rear of the frame, said trail having a lunette at the end thereof, a flexible member connecting the front hooks to the lunette and the lunette to the rear hooks, and a winch 95 mechanism on said frame.

4. In combination with a field gun having a trail, a device of the class described comprising a rectangular frame, removable pegs for said frame adapted to maintain the 100 frame above the trail, abutting members from the frame to the trail, hooks at the sides adjacent the front and at the rear adjacent the sides of the frame, said trail having a lunette, a flexible member connected with one end to one of the hooks at the side, then passing through the lunette, then through a hook at the rear adjacent the side to which the end is attached, then through the other rear hook, then back 110 through the lunette to the other side hook where the other end of the flexible member is secured, and a winch mechanism on said frame.

In testimony whereof I have signed my 115 name to this specification in the presence of two subscribing witnesses.

JOHN SMITH.
